UNITED STATES PATENT OFFICE.

WILLIAM T. SMITH, OF PHILADELPHIA, PENNSYLVANIA.

DESIGN FOR A WOVEN RUG.

41,868.

Specification for Design. Patented Oct. 24, 1911.

Application filed April 28, 1911. Serial No. 623,992. Term of patent 14 years.

To all whom it may concern:

Be it known that I, WILLIAM T. SMITH, a citizen of the United States, residing in Philadelphia, Pennsylvania, have invented a certain new, original, and ornamental Design for a Woven Rug, of which the following is a specification, reference being had to the accompanying drawing, forming part thereof.

The figure is a plan view of the woven rug showing my design.

I claim—

The ornamental design for a woven rug, as shown.

WILLIAM T. SMITH.

Witnesses:

G. W. HELMAN,
R. C. STERNER.
